UNITED STATES PATENT OFFICE.

JAMES A. THOMAS, OF TROY, NEW YORK, ASSIGNOR TO CLUETT, PEABODY & CO., INC., OF TROY, NEW YORK, A CORPORATION OF NEW YORK.

STOP MOTION.

1,411,198.

Specification of Letters Patent. Patented Mar. 28, 1922.

Application filed April 28, 1920. Serial No. 377,380.

To all whom it may concern:

Be it known that I, JAMES A. THOMAS, a citizen of the United States of America, residing at Troy, in the county of Rensselaer 5 and State of New York, have invented new and useful Improvements in Stop Motions, of which the following is a specification.

Reference may be had to the accompanying drawings, and the reference characters 10 marked thereon, which form a part of this specification. Similar characters refer to similar parts in the several figures therein.

This invention relates to improvements in stop-motion mechanism for sewing-machines 15 of various kinds.

The principal object of the invention is to provide a mechanism controlled by the thread under tension, and which when released from the control of the thread will 20 automatically quickly stop the operation of the machine.

Other objects will appear in connection with the following description.

Fig. 1 of the drawings is a view in side 25 elevation of a sewing-machine provided with my improved stop-motion mechanism.

Fig. 2 is a top plan view of the same.

Fig. 3 is a view in elevation of the front 30 end of the machine.

Fig. 4 is a view in elevation of the rear 35 end of the machine partly broken away.

Fig. 5 is a view in side elevation of a broken-away part of the machine and stop-motion mechanism, including the thread-controlled member, shown on a larger scale 40 than in Fig. 1.

Fig. 6 is a top plan view of a broken-away portion of the mechanism shown in Fig. 3.

Referring to the drawings wherein the 45 invention is shown in preferred form, 1 is the bed-plate of a sewing-machine having the overhanging arm, 2, and head, 3, two presser-feet, 4, needle, 5, needle-bar, 6, tension, 7, thread-guides, 8 and 9, take-up, 10, 50 check-spring, 11, balance-wheel, 12, main-shaft, 13, fixed pulley, 14, loose pulley, 15, and driving-belt, 16, adapted to be shifted from one to the other of the pulleys, 14 and 15, the several parts designated being 55 parts of a well known type of sewing-machine particularly adapted for hem-stitching fabrics.

In the operation of said machine, transverse vibrating movements are imparted to 55 the needle-bar, 6, by means of a link, 17,

connecting said needle-bar with a rocker-arm, 18, fixed upon a cross-shaft, 19, to which rocker-arm vibrating movements are imparted by means of a cam-follower, 20, on the rocker-arm which engages a cam-groove, 21, in a cam, 22, which is rotated in the operation of the machine.

As the parts above described constitute no feature of my invention a detailed description of the same is deemed unnecessary; 60 and for an understanding of the present invention it will be sufficient to merely bear in mind that the shaft, 19, has imparted to it in the operation of the machine a rapid rocking movement.

The belt, 16, is shifted from time to time from one to the other of the pulleys, 14 and 15, by means of a fork, 23, carried by a rocker-arm, 24, fixed upon a rock-shaft, 25, rockably mounted upon a bracket, 26, fixed 70 upon the base, 27, of the arm, 2.

A brake-arm, 28, is also fixed upon the rock-shaft, 25, just below the balance-wheel, 12, in position to be automatically moved into engagement with the balance-wheel as the shaft, 25, is rotatively moved in a direction to cause the belt to be shifted from the fixed pulley, 14, to the loose pulley, 15, whereby as the fixed pulley, 14, and the movable parts of the machine operated 80 thereby are relieved from the driving impulse of the belt, 16, the brake, 25, will automatically be applied to the balance-wheel, 12, to quickly overcome the momentum of the moving parts of the machine. 90

Rocking movements are imparted to the shaft, 25, by means of a rocker-arm, 29, fixed upon the shaft and connected by a link, 30, with the lower end of a lever, 31, fulcrumed at 32, upon the overhanging arm, 2, of the machine.

The upper portion of the lever, 31, is connected by a coil-spring, 33, with the arm, 2, at 34, which spring acts to move the lever, 31, and the parts connected therewith in a 100 direction to shift the belt, 16, from the fixed pulley, 14, to the loose pulley, 15, when said lever, 31, is released to the action of said spring.

A rod, 35, pivotally connected at 36 with the lever, 31, at a point above its fulcrum is mounted to reciprocate longitudinally through a slideway, 37, formed on a bracket, 38, mounted upon the side of the head, 3.

The front end of the rod, 35, which pro-

- jects through the slideway, 37, is formed or provided with a shoulder, 39, which in the forward position of the rod is adapted to be engaged by a detent, 40, pivoted at 41, and serving when in engagement with said shoulder, 39, to releasably hold the rod, 35, in its forward position with the spring, 33, under tension. The detent, 40, is disengaged from the shoulder, 39, by an upward 5 swinging movement upon its pivotal connection, 41, to the position shown in Fig. 5; and when the shoulder, 39, is thus released from the control of the detent, a rearward movement is automatically imparted by the spring, 33, to the rod, 35, at the same time that the spring actuates the belt-shifting mechanism to shift the belt from the fixed pulley, 14, to the loose pulley, 15.
- 20 The detent, 40, has a flange, 42, adapted to be engaged at certain times by a cam, 43, fixed upon a longitudinally reciprocating rock-shaft, 44, mounted in bearings on the bracket, 38, whereby a forward longitudinal 25 movement of the shaft, 44, when the cam, 43, is in line with the flange, 42, will cause the detent to be swung upward as shown in Fig. 5.

An offset, 45, fixed upon the shaft, 44, by 30 means of the same hub or sleeve, 46, as that from which the cam, 43, projects, is adapted to be moved by rocking movement of the shaft, 44, into and out of the path of a rod, 47, reciprocating through a slideway, 48, 35 formed on the bracket, 38, and pivotally connected at its rear end at 49, with a rocker-arm, 50, fixed upon the rock-shaft, 19, which it will be remembered is rapidly oscillated or rocked in the operation of the 40 machine.

In the operation of the machine rapid longitudinal reciprocating movements are thus imparted to the rod, 47.

Fixed upon the front end of the rock-shaft, 44, is an arm, 51, provided with an eye, 52, adapted to receive the stretch of thread, 53, between the tension, 7, and the thread-guide, 9.

This arm, 51, is so fixed upon the shaft, 44, that when the eye, 52, is engaged by the thread under tension the offset, 45, on the shaft, 44, will be at one side of the path of the rapidly reciprocating rod, 47.

A counter-balance, 54, tends to rotate the shaft, 44, in a direction to move the offset, 45, into the path of the rapidly reciprocating rod, 47, but the counter-balance is ineffective to thus rotate the shaft, 44, so long as the arm, 51, is under the control of the 60 thread under tension.

The operation of the stop-motion-mechanism is as follows:—

The machine being in operation, driven by the belt, 16, in engagement with the fixed pulley, 14, and the parts in the position

shown in Fig. 1 with the arm, 51, under the control of the thread under tension, and the rod, 35, held in its forward position by the detent, 40, upon the breaking or failing of the thread, 53, the rock-shaft, 44, is automatically rotated by the counter-balance, 54, bringing the offset, 45, into the path of the rapidly reciprocating rod, 47, which immediately impinges against said offset thereby forcing the shaft, 44, with said offset and 70 the cam, 43, forwardly, thus forcing the cam, 43, to engage the flange, 42, on the detent, 40, and raise the detent to the position shown in Fig. 5, thus disengaging the detent from the shoulder, 39, on the rod, 35. 80

The spring, 33, being thus released from the control of the rod, 35, causes the lever, 31, to be moved in a direction to actuate the belt-shifting-mechanism in a direction to shift the belt from the fixed pulley, 14, to 85 the loose pulley, 15, thus discontinuing the application of driving power to the machine while at the same time the brake, 28, is drawn against the balance-wheel, 12, to overcome the momentum of the moving 90 parts of the machine.

After the arm, 51, has again been placed under the control of the thread, 53, the machine can be started and the stop-motion mechanism reset by moving the lever, 31, in 95 opposition to the force of the spring, 33, by means of an arm, 55, fixed upon said lever the detent, 40, automatically making rocking engagement with the shoulder, 39, as the rod, 35, is thus moved forward. 100

The coil-spring, 56, tends to impart to the shaft, 44, a movement in a direction opposite to that imparted to the shaft by means of the rod, 47.

I have shown and described my invention 105 in its application to a well known type of sewing-machine, but it is also applicable to various other machines employing thread under tension.

What I claim as new and desire to secure 110 by Letters Patent is—

1. In a sewing-machine and in combination, a member vibratory in the operation of the machine; a rod connected with said member to be longitudinally reciprocated thereby; a longitudinally slidable rock-shaft; an offset on said rock-shaft movable by rocking movement of the shaft into and out of the path of said rod; a cam carried by 115 said rock-shaft; a thread-engaging member whereupon said rock-shaft is supported in the normal operation of the machine with said offset removed from the path of said rod, means being provided whereby said rock-shaft when released from the control of the 120 thread automatically assumes a position with said offset in the path of said rod; belt-shifting-mechanism automatically actuated to stop the machine and having a rod formed 125 with a shoulder; a detent removably engage- 130

able with said shoulder for preventing automatic operation of the belt-shifting-mechanism, said detent having a member located in the path of said cam when said offset 5 is located in the path of said rod.

2. In a sewing-machine and in combination, a shaft rapidly rocked in the operation of the machine; a rocker-arm on said shaft; a rod connected with said rocker-arm where- 10 by longitudinal reciprocating movements are imparted to the rod; a longitudinally slidably rock-shaft; an offset on said rock-shaft movable by rocking movement of the shaft into and out of the path of said rod; 15 a cam carried by said rock-shaft; a thread-engaging member whereby said rock-shaft is supported in the normal operation of the

machine with said offset removed from the path of said rod, means being provided whereby said rock-shaft when released from 20 the control of the thread automatically assumes a position with said offset in the path of said rod, belt-shifting-mechanism automatically actuated to stop the machine and having a rod formed with a shoulder; a 25 detent removably engageable with said shoulder for preventing automatic operation of the belt-shifting-mechanism, said detent having a member located in the path of said cam when said offset is located in the path of 30 said rod.

In testimony whereof, I have hereunto set my hand this 20th day of April, 1920.

JAMES A. THOMAS.
